(57) **CLAIM**

The ornamental design for a display board, as shown and described.

DESCRIPTION

FIG. 1 is a three-quarter perspective view from above of a display board in accordance with a first embodiment of our Design;

FIG. 2 is a front elevational view corresponding to FIG. 1; FIG. 3 is a rear elevational view corresponding to FIG. 1;

FIG. 4 is an elevational view from the left in FIG. 1;

FIG. 5 is an elevational view from the right in FIG. 1;

FIG. 6 is a top plan view;

FIG. 7 is a bottom plan view;

FIG. 8 is a view similar to FIG. 1 illustrating a second embodiment of our Design; the other views are the same as FIGS. 2 to 7 respectively; and,

FIG. 9 is a view similar to FIG. 1 illustrating a third embodiment of our Design; the other views are the same as FIGS. 2 to 7 respectively.
